UNITED STATES PATENT OFFICE.

HARRY LOWE, OF MONTPELIER, VERMONT.

NOSE-BAND FOR OVERDRAW-CHECKS FOR BRIDLES.

SPECIFICATION forming part of Letters Patent No. 319,916, dated June 9, 1885.

Application filed March 19, 1885. (No model.)

To all whom it may concern:

Be it known that I, HARRY LOWE, of Montpelier, in the county of Washington and State of Vermont, have invented a new and useful Improvement in Nose-Bands for Overdraw-Checks for Bridles, which improvement is fully set forth in the following specification and accompanying drawings, in which—

Figure 1 is a view of the adjustable nose-band all complete. Fig. 2 shows the same affixed to an overdraw-check.

The object of my invention is to furnish a device that is perfectly secure in any position, and which can be put on or taken off in a moment's time, and that can be easily and quickly adjusted, so that the driver can fit it to the horse he is driving by lowering it on the check-rein so that the band will come across the nose just above the nostrils, or raising it higher on the check-rein to any desired position.

It will be seen that this adjustable band can be put onto the check-rein in a moment by holding the check-rein so that the rein and band cross each other in the form of the letter X. Then pass the tongue C through the hole in the check-rein, and then bring the rein around into line with the band, slipping the rein sidewise into the hooks. By having holes in the check-rein at different points the band can be fixed in any position desired.

It is necessary that the leather band be some-

thing in the shape of a crescent or half-circle, in order to have the band and check fit well to the horse's head, and when the nose-band 35 is taken off it leaves the check-rein in just as good shape as though no attachment had been made.

In the drawings, A is the leather portion of the adjustable nose-band of a crescent shape, 40 except the ends are left a little wider than the check-rein, instead of coming to a point.

b b are devices made of metal in pairs, one to be attached to each end of the leather band by rivets. The devices have hooks near each 45 end, and are so made that when they are fastened onto the leather band the hooks nearest each end of the leather band turn outward or downward, while the hooks on the opposite ends turn inward toward each other or upward. 50

C is the tongue of these devices, midway between the hooks, which is to pass through the hole in the check-rein.

Having thus described my invention, what I claim as new, and desire to secure by Letters 55 Patent, is—

The combination of the leather band A with the metallic devices b b, adapted for attachment to the straps of an overdraw-check, as and for the purposes set forth.

HARRY LOWE.
